UNITED STATES PATENT OFFICE.

WILLIAM F. SCATTERDAY AND JOHN LAWRENCE PORTER, OF COLUMBUS, OHIO.

GAS-BURNER.

No. 863,658.

Specification of Letters Patent.

Patented Aug. 20, 1907.

Application filed January 4, 1907. Serial No. 350,703.

To all whom it may concern:

Be it known that we, WILLIAM F. SCATTERDAY and JOHN LAWRENCE PORTER, citizens of the United States, residing at Columbus, in the county of Franklin and State of Ohio, have invented certain new and useful Improvements in Gas-Burners, of which the following is a specification.

Our invention relates to gas burners and has for its object the provision of a device of this character constructed in such manner that the proportions of air and gas may be readily regulated, and constructed in such manner that a plentiful supply of air may be obtained.

Further objects and advantages of the invention will be set forth in the detailed description which now follows:

In the accompanying drawing: Figure 1 is a vertical section of a gas burner constructed in accordance with the invention, illustrating the gas valve and pipe upon which it is supported, in elevation, and, Fig. 2 is a horizontal section upon line xx of Fig. 1.

Like numerals designate corresponding parts in both of the figures of the drawing.

Referring to the drawing, the numeral 5 designates a gas supply pipe and the numeral 6 designates a valve controlling the flow of gas from the pipe 5 to the nipple 7. Brackets 8 serve to support a cup 9, the bottom of this cup forming a spider 10. The cup 9 supports a cylindrical casing 11 which is closed at the top and is perforated around its sides adjacent the top as at 12. A plate 13 spans this casing and is provided with a depending funnel 14, this funnel opening through the plate 13 as at 15. A tube 16 is centrally located within the casing 11, extends through the funnel 14 and is threaded at 17 into the spider, said spider being enlarged as at 18 for this purpose. A lock nut 19 serves to retain the tube 16 in its adjusted position, it being understood that this tube may be screwed up or down for a limited distance. Threaded upon the lower end of the tube 16 is a sleeve 20 which lies over the nipple 7.

The operation of the device is as follows: Gas is admitted through the valve 6, passes through the nipple 7 and sleeve 20 to the pipe 16. During its passage from the nipple 7 to the sleeve 20, a certain quantity of air is mixed with the gas and the proportions between the air and gas may be readily determined by screwing the sleeve 20 up or down upon the tube 16. The air and

gas passes from the upper end of the tube 16 and through the openings 12 to the upper outside portion of the casing 11, where it is ignited, the gas burning around the edge of this casing and forming a pointed flame above 50 said casing. Air also passes between the arms of the spider and up through the funnel 14 mixing with the air and gas from the tube 15 at the upper end of said tube and providing a perfect combustion. Screws 21 provide means for securing the casing 11 to the cup 9. 55

It has been found that a burner constructed as herein shown and described, produces a clear blue flame indicative of perfect combustion and yields a maximum degree of heat.

While the elements shown and described are well 60 adapted to serve the purposes for which they are intended, it is to be understood that the invention is not limited to the precise construction set forth, but includes within its purview such changes as may be made within the scope of the appended claims. 65

What we claim, is:

1. In a device of the character described, the combination with a casing which is closed at the top and open at the bottom and which has a series of openings formed through the wall thereof adjacent said closed top, of a 70 tube centrally located within said casing and terminating between the top of the casing and the center of the casing, an inverted funnel surrounding said tube, a plate which supports said funnel and which closes the casing around said funnel, a mixing sleeve located upon the lower end of 75 the tube, and a gas nozzle adapted to discharge into said mixing sleeve.

2. In a device of the character described, the combination with a casing which is closed at the top and open at the bottom and which has a series of openings formed 80 through the wall thereof adjacent said closed top, of a tube centrally located within said casing and terminating between the top of the casing and the center of the casing, an inverted funnel surrounding said tube, a plate which supports said funnel and which closes the casing around 85 said funnel, a mixing sleeve located upon the lower end of the tube, said tube being vertically adjustable within the casing and said sleeve being vertically adjustable upon the tube and a gas nozzle adapted to discharge into said mixing sleeve. 90

In testimony whereof we affix our signatures in presence of two witnesses.

WILLIAM F. SCATTERDAY.
JOHN LAWRENCE PORTER.
